UNITED STATES PATENT OFFICE.

ALICE J. MACQUEENE, OF WINNETKA, ILLINOIS.

SKIRT AND DRESS-WAIST RETAINING DEVICE.

SPECIFICATION forming part of Letters Patent No. 727,167, dated May 5, 1903.

Application filed November 14, 1902. Serial No. 181,299. (No model.)

To all whom it may concern:

Be it known that I, ALICE J. MACQUEENE, of Winnetka, in the county of Cook and State of Illinois, have invented certain new and useful Improvements in Retaining Devices for Shirt-Waists and Dress-Skirts; and I do hereby declare that the following is a full, clear, and exact description thereof, reference being had to the accompanying drawings, and to the letters of reference marked thereon, which form a part of this specification.

This invention relates to a novel device for holding or retaining in its proper position the lower front part of a shirt-waist, more particularly of the kind which is designed for producing what is known as a "straight-front" effect, and for holding down the dress-skirt band to produce a "dip-front" effect.

The invention consists in the matters hereinafter set forth, and more particularly pointed out in the appended claim.

In the drawings, Figure 1 illustrates the application of my improvement to a shirt-waist, the dress-skirt being dropped down to show the application of my novel device to the shirt-waist. Fig. 2 illustrates the effect of the device at the front of the skirt-band. Fig. 3 is a vertical section of a corset to which the device is adapted to be attached, showing the device in position thereon, and the manner of securing the shirt-waist belt and skirt to the retaining device. Fig. 4 is a front perspective view of the device removed from the waist. Fig. 5 is a rear perspective view thereof.

As shown in the drawings, the retaining device consists of a straight rigid sheet-metal plate A, which is provided at its upper end with an outwardly and downwardly turned hook A' and a stiff metal pin B, which is affixed at one end to the rear face of the plate A, adjacent to the end remote from the hook A'. The connection between the pin B and the strip A may be further strengthened by providing the lower end of the plate with a lip or extension a, which is adapted to be folded upwardly over the lower end of the pin.

The application of the device described for retaining or holding down the lower front part of the shirt-waist is shown in Figs. 1, 2, and

3. Said device is located at the juncture of the waist and skirt and extends both above and below said juncture. The pin B is inserted upwardly into the corset D to hold the 55 same laterally in place. Conveniently said pin is inserted into the pocket containing one of the stays D' of the corset, so that there is no liability of the point of the pin piercing the corset and injuring the wearer. Said pin 60 B is also inserted through the free end c of the belt C of the shirt-waist C' and through the skirt of the waist or that part below the belt, whereby the front lower part of the 65 waist is held down in place. The ends of the belt may be secured together at the front of the waist by a buckle or may be tied, and in either case the free end of the belt is drawn downwardly tightly against the corset or a garment outside of the corset and the pin 70 thrust diagonally upwardly through the free end of the belt and into the corset in the manner shown in Fig. 3. The hook-plate A is located outside of the shirt-waist and between the skirt-band and the corset, and the hook 75 A' hooks over the upper margin of and acts to pull or draw the front central part thereof downwardly, as shown in Fig. 2, thereby giving a dip effect to the upper part of the skirt. The attachment of the pin B of the device to 80 the waist serves to hold down the lower front part of the waist and to keep the front of the waist straight. The part of the hook shown as displayed above the skirt-band is concealed by the belt worn over the skirt-band and may 85 be further concealed by a brooch clasped or secured to the belt immediately over said hook.

When the holding device is in place and the skirt-band fastened, said band presses the plate or strip A closely against the corset, 90 and the hook A' is made narrow, so as to produce no objectionable protuberance at the front of the waist, said hook being only wide enough to receive the skirt-band.

The connection of the pin rigidly with the 95 plate by either of the means described is of great advantage, for the reason that it strengthens the device as a whole and prevents the pin becoming bent or doubled upon itself or detached from the plate.

I claim as my invention—

A device for holding down the lower front

part of a shirt-waist and the upper front part of a dress-skirt comprising a narrow plate provided at its upper end with a forwardly and downwardly extending hook and a sharp-
5 ened shank made longer than said plate and straight throughout its length, the free end of said shank diverging from said plate, the lower end of said plate being folded back-
wardly and upwardly parallel with the plate,
10 and formed to provide a socket in which the lower end of the shank is seated, said folded

part constituting a rigid connection of the shank with the plate.

In testimony that I claim the foregoing as my invention I affix my signature, in presence 15 of two witnesses, this 10th day of November, A. D. 1902.

ALICE J. MACQUEENE.
